CLAIM

The ornamental design for a pressurized vessel for a water closet flushing system, as shown.

DESCRIPTION

FIG. 1 is a top plan view of the pressurized vessel for a water closet flushing system in accordance with the present invention;

FIG. 2 is a front view of the pressurized vessel of FIG. 1; FIG. 3 is a bottom plan view of the pressurized vessel of FIG. 1;

FIG. 4 is the pressurized vessel of FIG. 1 as seen from the left hand side of FIG. 2;

FIG. 5 is the pressurized vessel of FIG. 1 as seen from the right hand side of FIG. 2; and,

FIG. 6 is a rear view of the pressurized vessel of FIG. 1. The broken lines shown in the drawings are for illustrative purposes only and form no part of the claimed design.
